PEDESTRIAN BRIDGE

James H. Rock, 411 Orchard St., Sewickley, Pa.

Filed Apr. 16, 1965, Ser. No. 84,825

Term of patent 14 years

(Cl. D13—1)

FIGURE 1 is a top plan view of the pedestrian bridge;
FIGURE 2 is a view in side elevation of the pedestrian bridge illustrated in FIGURE 1;

FIGURE 3 is a perspective view of another species of my pedestrian bridge.

FIGURES 1 and 2 are broken away to indicate the bridge span is of indeterminate length.

I claim:

The ornamental design for a pedestrian bridge, substantially as shown and described.
